(57) **CLAIM**

I claim the ornamental design for a surveillance camera, as shown and described.

DESCRIPTION

FIG. 1.1 a front view of a surveillance camera, showing my new design;

FIG. 1.2 is a back view thereof;

FIG. 1.3 is a left view thereof;

FIG. 1.4 is a right view thereof;

FIG. 1.5 is a top view thereof;

FIG. 1.6 is a bottom view thereof; and

FIG. 1.7 is a back perspective view thereof.

The dashed lines in the drawings depict portion of the surveillance camera that form no part of the claimed design.
